UNITED STATES PATENT OFFICE.

LEE DE FOREST, OF NEW YORK, N. Y., ASSIGNOR TO GEORGE K.
WOODWORTH, OF BOSTON, MASSACHUSETTS.

SPACE TELEGRAPHY.

No. 850,917.

Specification of Letters Patent.

Patented April 23, 1907.

Application filed January 29, 1907; Serial No. 354,687.

To all whom it may concern:

Be it known that I, LEE DE FOREST, a citizen of the United States, and a resident of New York, in the county of New York and State of New York, have invented a new and useful Improvement in Space Telegraphy, of which the following is a specification.

My invention relates to space telegraphy and more especially to transmitting systems in which an energizing-circuit, commonly known as the "singing-arc" circuit and including a condenser and means for producing an electric arc, is employed to produce high-frequency vibratory currents.

The object of my invention is to improve and increase the efficiency of such singing-arc circuit.

With this object in view my invention broadly stated comprises a singing-arc circuit and means for maintaining an atmosphere of steam about the electric arc which is included in said circuit.

Specifically my invention comprises several forms of construction in which the heat of the arc itself causes the vaporization of a quantity of water, thereby to produce an atmosphere of steam about the arc.

Although for the purpose of more fully disclosing my invention I have illustrated in the drawings accompanying and forming a part of this specification several specific embodiments of said invention which have proved very efficient in practice, it will be understood that I do not limit myself to the particular constructions herein disclosed inasmuch as many modifications may be made therein without departing from the principle of my invention.

Figure 1 represents a space-telegraph transmitting system constructed in accordance with my invention, the figure being partly in diagram and partly in section. Figs. 2, 3 and 4 show partly in diagram and partly in section other forms of space-telegraph transmitting system embodying the principle of my invention.

In all the figures V is an antenna, L is an autotransformer, E is an earth connection, C is a condenser, D is a generator herein shown as a direct-current generator, K is a key and 1 is an electrode preferably of carbon. In Figs. 1, 2, 3 and 4, respectively, 2, 2', 2'', and 2''' are electrodes which may be of metal and preferably are of brass or

In all the figures the arc-electrodes are included in circuit with the condenser C and, as shown, with the inductance L. The circuit which includes the aforesaid arc-electrodes, condenser C and inductance L is a singing-arc circuit or a producer of practically continuous undamped electrical oscillations when energized with a direct-current source, and when energized with an alternating-current source said circuit becomes the seat of trains of oscillations which, although not continuous, are of great persistency.

In Fig. 1, the electrode 1 is secured to but insulated from the casing 7 by the insulating bushing 8. The electrode 2 which consists of a raised ring secured to or forming a part of the plate 17 is perforated at 9 to allow the passage therethrough of steam generated by heating the water 5 which is contained in the receptacle 7. One way in which the water may be heated consists as shown in Fig. 1 in attaching members 4 of good heat conductivity to the plate 17 and permitting them to project into the water. The steam which condenses in the upper portion of the receptacle 7 causes water to collect on the depressed portions of the plate 17 and drop through said plate by way of the apertures 10.

In Fig. 2, the electrode 1 is secured to and insulated from the casing 11 by the bushing 8'. The pump 15 working in the pump-chamber 14 furnishes a supply of water for the hollow electrode 2', said water being conducted thereto by way of the pipe 13. The heat of the arc causes the water within the electrode 2' to vaporize and a jet of steam thereby is blown across the arc by way of the passage 16.

In Fig. 3, the electrode 2'' consists of a cylinder which may be removed from the cylinder 13' when it becomes sufficiently consumed to impair the efficiency of the arc. The cylinder 13' may be supported on a base 13'' and may be supplied with water from the tank 12 by way of the pipe 12' which is provided with the valve 16.

In Fig. 4, the water 5 in the receptacle 12 is heated by means of the resistance-coil 19 which is connected in series with the generator D and the electrodes 1 and 2''. The electrode 2''' may be provided with the flange 18 to prevent the water from bubbling up into the arc itself and causing irregularities in the behavior thereof. The elec-

trode 1 may be insulated from the casing 12 by means of the bushing 20 and the leads to the heating-coil may be insulated from said casing by the bushings 21, 22.

5 Although in Fig. 3 I have shown one embodiment of my invention in which the arc is not inclosed, I prefer as shown in Figs. 1, 2 and 4, to inclose the arc in a receptacle thereby to increase the energy absorbed by the 10 singing-arc circuit in virtue of the higher potentials which may be developed between the arc-electrodes due to increasing the pressure of the medium surrounding the same. Also 15 all loss of steam by evaporation is prevented by inclosing the arc, thereby obviating the necessity for an arrangement such as shown in Fig. 3 in which the valve 16 supplies water to the electrode 2" to take the place of water lost by evaporation.

20 In Fig. 4, the impedance of the coil 19 as well as that of the inductance L' prevents the high-frequency oscillations from traversing the leads from the generator D. The rheostat R, which is bridged across the coil 19, 25 permits the direct regulation of the current flowing across the arc itself.

I claim—

1. In a space-telegraph transmitting system, a circuit including a condenser and 30 means for producing an electric arc, in combination with means for maintaining an atmosphere of steam about said arc:

2. In a space-telegraph transmitting system, a circuit including a condenser and

means for producing an electric arc, in combination with means for producing and maintaining an atmosphere of steam about said arc. 35

3. In a space-telegraph transmitting system, a singing-arc circuit and means for maintaining an atmosphere of steam about the electric arc included therein. 40

4. In a space-telegraph transmitting system, a singing-arc circuit and means for producing and maintaining an atmosphere of 45 steam about the electric arc included therein.

5. In a space-telegraph transmitting system, a singing-arc circuit having its arc-electrodes immersed in an atmosphere of steam. 50

6. In a space-telegraph transmitting system, a circuit including a condenser and arc-electrodes, a casing having said electrodes secured therein, a quantity of water in said casing and means for vaporizing said water. 55

7. In a space-telegraph transmitting system, a circuit including a condenser and arc-electrodes, a casing having said electrodes secured therein, a quantity of water in said casing, and members of good heat conductivity secured to one of said electrodes and 60 projecting into said water.

In testimony whereof I have hereunto subscribed my name this 4th day of January 1907.

LEE DE FOREST.
